UNITED STATES PATENT OFFICE.

MORRIS NOVER, OF NEW YORK, N. Y.

HAND-BAG.

1,084,101.

Specification of Letters Patent. Patented Jan. 13, 1914.

Application filed June 20, 1912. Serial No. 704,837.

To all whom it may concern:

Be it known that I, MORRIS NOVER, a citizen of the United States, and a resident of New York, county and State of New York, 5 have invented certain new and useful Improvements in Hand-Bags, of which the following is a full, clear, and exact description.

This invention relates more particularly 10 to a hand bag for the use of women and in which is arranged a secret pocket. In devices of this kind as ordinarily constructed, the bag is provided with a number of pockets and has the back thereof continued 15 to form a flap which serves as a closure for the open ends of the various pockets, but the backing and flap are ordinarily used for no other purpose than as a closure and thus the bag as a receptacle is much more 20 limited than is the case with the present invention wherein the back and flap member is so made as to form a pocket adapted for the reception of various articles.

One of the principal objects therefore of 25 the invention is to provide a hand bag or similar article in which the back and flap member may be made to form a secret pocket to receive various articles and without materially increasing the size or affecting the 30 general appearance of the bag as ordinarily made.

A further object of the invention is to provide a secret pocket of considerable length which may extend substantially the 35 entire length of the flap and back member and which has independent means for closing the same and which is adapted to be folded with the flap portion.

With these and other objects in view, the 40 invention will be hereinafter more particularly described with reference to the accompanying drawings, which form a part of this specification, and will then be pointed out in the claim at the end of the description.

45 In the drawings, Figure 1 is a perspective view of one form of device embodying my invention and looking at the front. Fig. 2 is a perspective view, partly in section, looking at the rear of the device. Fig. 3 is a 50 plan view with the back and flap member open; and Figs. 4 to 7 are fragmentary vertical sections showing slightly different forms of the invention.

The bag or device has a body 10 formed 55 with or without a frame and comprises a

plurality of pockets to receive various articles and which may be of the usual or of any preferred construction. The body 10 may have the usual strap 11 for carrying purposes and at the forward portion thereof has a socket member 12 which is adapted to receive the button member 13 of a suitable fastener in the usual way. The button member 13 of the fastener is held to the flap portion 14 forming a continuation of the back 15 as usual, the said flap 14 and back 15 forming a single member 16.

A secret pocket 17 is provided which may extend substantially the entire length and width of the member 16 so as to form a part 60 of the back of the body 10 and the flap 14. This pocket is formed by a member 18 which is secured along its edges to the member 16 by stitching or otherwise, and at the upper portion thereof is provided with button members 19 which are adapted to engage the socket members 20 of suitable fasteners of the usual or any preferred kind, and which are adapted to close the pocket when 65 not in use. It will thus be evident that the 70 pocket serves to utilize a part of the back not otherwise used and forms a handy receptacle for various articles, and the pocket whether containing articles or otherwise 75 may be folded over so that the flap may 80 close the pockets in the body 10 by the engagement of the members 12 and 13 of the 85 fasteners in the usual way, and should the bag open by accident as often occurs, the articles contained in the pocket 17 are less 90 likely to be lost than those contained in the pockets of the body 10.

In Fig. 4, the construction is substantially the same as shown in Figs. 1 to 3, except that the pocket instead of being secured along the vertical edges is provided with a gusset 21 to increase its capacity. In this case, the upper end of the pocket may be closed by a short flap 22 having a fastener member 23 which is adapted to 95 engage a fastener member 24, the whole flap and pocket being folded over in a manner 100 similar to the construction shown in Fig. 1 and the usual hand bag.

In Fig. 5, the construction differs from 105 that described in that a partition 25 is provided which divides the secret pocket into two parts 26 and 27 each adapted to independently receive articles.

The construction shown in Fig. 6 is sub- 110

stantially the same as that shown in Fig. 1, except that the pocket is open at the bottom instead of the top, and a short flap 28 is provided having a fastening element 29 which is adapted to engage the fastener member 30 to close the open end of the pocket.

Fig. 7 differs from Fig. 1 mainly in that the member 18 of the pocket is provided 10 with one or more supplementary pockets 31 on the outside thereof, the said pockets having their ends open at 32 at the bottom thereof to receive small articles as cards, car tickets and the like.

15 From the foregoing, it will be seen that simple and efficient means is provided whereby a hand bag may be formed with a large secret pocket; that said pocket may be applied to the hand bag as ordinarily 20 constructed without materially affecting its general appearance and at the same time increasing its capacity; and that said pocket does not materially increase the cost of manufacture of the article.

25 Having thus described my invention, I

claim as new and desire to secure by Letters Patent:—

A hand bag comprising a body having a front and a back portion, a handle attached to the said body, a flap forming a continuation of the back portion, a member extending substantially the entire length and width of the back member and flap and secured thereto along the edges and lower end of the back portion to form a pocket 35 opening at the free end of the flap, a button and socket fastener for securing the open end of said pocket and another similar fastener for securing the flap to the front of the body, the outer part of said pocket 40 or flap extending beyond the end of the inner part or member and carrying the button member of one fastener and the socket member of the other fastener.

This specification signed and witnessed 45 this 13th day of June A. D. 1912.

MORRIS NOVER.
